(57) **CLAIM**

The ornamental design for a graphical user interface for a display screen, as shown and described.

DESCRIPTION

FIG. 1 is a front view of a graphical user interface for a display screen showing our new design; and,

FIG. 2 is a front view of another graphical user interface for a display screen showing an alternative embodiment thereof. The broken line showing of various regions is for illustrative purposes only and forms no part of the claimed design. The broken line showing of the display screen is for illustrative purposes only and forms no part of the claimed design.

1 Claim, 2 Drawing Sheets

FIG. 1

FIG. 2
